ANTISIPHONIC TOILET FLUSH TANK

Jesse C. Owens, Los Angeles, Calif.

Application August 29, 1945, Serial No. 613,310

7 Claims. (Cl. 4—44)

1

My invention relates to an anti-siphonic toilet flushing tank of the general type disclosed in my co-pending applications for U. S. Letters Patent filed February 15, 1943, Serial No. 475,863, issued as Patent No. 2,412,691, December 17, 1946, and Serial No. 570,147, filed December 28, 1944, also U. S. Letters Patent No. 2,372,848, issued to me April 3, 1945, on Toilet tank outlet fitting and elbow.

The principal objects of my invention are, to generally improve upon and simplify the construction of the tanks and flushing means disclosed in my aforesaid co-pending applications, to provide simple and effective means for positively counteracting and eliminating the possibility of the development of siphonic action in the tank, its valve and connections, tending to draw contaminated water into the tank and the fresh water supply pipe connected thereto; further to provide a valve and tank which are practically noiseless in operation, which desirable feature results from the employment of simple and efficient means for eliminating the gurgling and hissing noises ordinarily produced by the water passing into and from the tank, and further, to provide means for establishing and maintaining a rapid flow of flushing water into, through and from the tank and thereby materially shortening the period of the flushing and refilling functions.

Further objects of my invention are, to provide tank flushing means which may be built into the tank as an integral part thereof, or used as a replacement for the flushing means installed in tanks already in service, to provide adjustable means for controlling the action of the anti-siphonic means, and further, to provide flushing connections which may be located in different positions within the tank.

With the foregoing and other objects in view, my invention consists in certain features of construction and arrangement of parts which will be hereinafter more fully described and claimed and illustrated in the accompanying drawing, in which:

Figure 1 is a vertical longitudinal section taken through the center of a flushing tank with certain of the flush-producing parts built therein.

Figure 2 is a detail section of a valve used for directing the flow of water from the main inlet valve to the water flow-controlling means within the tank.

Figure 3 is a plan view of parts seen looking in the direction of the arrow 3 in Figure 1.

Figure 4 is a fragmentary vertical section taken on the line 4—4 of Figure 1.

2

Figure 5 is a vertical section similar to Figure 1, but showing a modified form of the water flow-control means within the tank and which is connected to the outlet thereof.

Figure 6 is a vertical section showing the substitution jet and silencing means applied directly to the outlet leading from the tank to the bowl.

Referring by numerals to the accompanying drawings, particularly to Figures 1, 2 and 3, 10 designates a flush tank preferably formed in a single piece from porcelain, plastics or the like and connected to the bottom thereof is a water supply pipe 11 and a discharge pipe 12 which leads to the bowl or urinal.

Connected to the supply pipe 11 is an upright pipe 13, carrying on its upper end a valve housing 14 having a main chamber 15 normally closed by a cap 16 screwed into the top of housing 14, and a short duct 17 connecting the upper end of pipe 11 with said chamber.

Formed integral with the bottom and side of housing 14 is a centrally disposed tubular member 18 provided in its upper end with a seat 19 for a diaphragm valve 20, preferably of rubber, which is clamped to housing 14 by the lower end of the cap 16.

Passing through and clamped to the center of diaphragm 20, is a tubular member 21 which depends from a shallow metal cup 22 seated on top of said diaphragm; and seated in said cup 22 is a disc 23 of rubber having a central aperture 24.

Passing through the tube 21 and aperture 24 is a vertical stem 25, smaller in diameter than said aperture; and on the upper end of said stem is a head 26 which normally closes aperture 24.

Seated in diaphragm 20 is an eyelet 27 which provides a bleed opening from the chamber 15; and loosely seated in said eyelet is a short piece of wire 28 having its ends 29 bent at right angles so as to retain it in said aperture. This member 28 moves lengthwise through eyelet 27 in response to varying water pressures, thereby acting as a cleaner to prevent the aperture through the eyelet from becoming clogged with sediment or the like.

Stem 25 extends downwardly through tubular member 18 and carries in position spaced above its lower end a disc 30 smaller in diameter than the internal diameter of the tube. Carried by the lower end of the stem 25 is a block 31 that is guided for vertical movement in the lower portion of tube 18.

Loosely arranged in a recess 32 in block 31, is 55 the end of an arm 33 which is pivoted at 34 on the

outside of the housing 14; and the outer end of the arm carries a float 35.

Formed in the top of arm 33 adjacent pivot 34 are notches 36 and 37, the latter being disposed outwardly from and being somewhat less in depth than notch 36.

Disposed above and at right angles to arm 33 and journaled in a bracket 38 on housing 14 and a bearing 39 in the side wall of tank 10, is a shaft 40 from which depends a finger 41, the lower end 10 of which normally rests in the deep notch 36 and which when the tank is flushed, moves into shallow notch 37.

A short arm 42 carrying a weight 43 projects horizontally from the shaft 40 within the tank 10, whereas a handle 44 is rigid with the shaft 40 outside the tank so as to be accessible to an operator. The handle 44 also extends horizontally, but in the direction opposite that in which the arm 42 extends so that downward motion of the handle 44 is at all times resisted by the weight 43, the purpose being to cause the weight 43 to return the handle 44 and the other associated parts to their original position after the water in the tank 10 has been evacuated, as will be described in greater detail hereinbelow.

Formed integral with and projecting upwardly from the bottom of tank 10 around the outlet opening to which discharge 12 is connected, is an upstanding tube 45 provided with an internal spiral rib 46 and a similar external spiral rib 47.

A sleeve 49 encircles the tube 45, the inside diameter of the sleeve 49 being slightly greater than the overall radius of the tube and its external spiral rib 47. The upper end of the sleeve 49 is closed by a top plate 48, preferably integral therewith, which rests upon the upper end of the tube 45. The lower end of the sleeve 49 is spaced a short distance above the bottom of the tank 10.

The inner face of the wall of sleeve 49 is spaced a slight distance away from the outer edge of external rib 47.

Seated in the center of plate 48 is the upper end of a depending tube 50, the lower end of which terminates just above the upper end of outlet pipe 12; and formed in the lower portion of the wall of said tube 50, are apertures 51. Tube 50 is spaced apart from the inner edge of internal flange 46. Seated in the upper end of outlet tube 12 is a short spiral deflector 52 very similar to the deflectors shown in my abovementioned Patent #2,372,848.

The upper end of a tube 53 is connected to the upper end of sleeve 49 where it extends through the sleeve to communicate with the interior thereof. This tube 53 extends downward to a point adjacent the lower end of said sleeve; and screw seated on the lower end of this tube, is a short tube 54. This tube 54 is adjustable inasmuch as it can be threaded to any selected position upon its supporting tube 53, thereby varying the elevation which the water in the tank must reach, while the tank is flushing before air will be drawn into the system through the tube 53 to break the siphonic flushing action.

Formed through the wall of the tube 45 just below its upper end are fairly large apertures 55 and formed through the wall of tube 50 just below plate 48 is a similar aperture 56.

Seated in the side of housing 14 and communicating with the bore of the tubular member 18 is the open upper end of an elbow 57 (see Figure 4), in the depending end of which is seated the end of a tube 58 which extends downward to a point

near the bottom of tank 10 and there leads horizontally into a short vertically disposed cylinder 59.

From the opposite side of cylinder 59, a tube 60 extends upward between the tube 45 and the sleeve 49, through one of the apertures 55 and thence to a point adjacent aperture 56 in tube 50, the parts being so arranged that a jet issuing from the tube 60 will be directed through the aperture 56 into the interior of the tube 50.

Arranged for reciprocatory movement within the cylinder 59 is a piston 61 provided in its lower portion with a diametrically disposed port 62 adapted to establish communication between the lower ends of tubes 58 and 60 when the piston is in its uppermost position (see Figure 2).

Formed through the upper portion of piston 61 is an inclined port 63 which when the piston is in its lowermost position establishes communication between the lower end of tube 58 and the interior of tank 10 (see Figure 1).

A rod 64 has its lower end pivotally connected to the piston 61 and its upper end to a short crank arm 65 that projects radially from shaft 40 substantially in parallelism with the arm 42 which carries the weight 43 (see Figure 3).

A short portion 66 of an open ended refill tube 37 extends through the upper portion of tube 58 and the vertical leg of elbow 57, the upper end of 30 said portion 66 terminating just above said elbow (see Figure 4); and from the lower portion of said tube 58, said refill tube extends to and through a plug 68 seated in the upper end of tube 50.

Formed through the wall of tube 58 within the 35 enlarged lower end of elbow 57, are air inlet apertures 69, which are for the purpose of admitting air to tube 58 and thus break siphonic conditions which might develop and tend to draw contaminated water from the bowl or urinal into the tank.

Under normal conditions or while inactive, the 40 operating parts of the flushing apparatus are positioned as illustrated in Figure 1, with float 35 on top of the water within tank 10 and acting through arm 33, block 31 and stem 25 to hold diaphragm 20 on its seat 19 thus cutting off flow of water through the valve.

Diaphragm 20 is also forced onto its seat 19 by pressure of water from supply pipe 13 which enters chamber 15 through the tubular rivet 27.

Under such conditions, finger 41 bears in recess 36 and arm 65 and rod 64 hold piston 61 at the lower end of its travel with port 62 out of registry with the tubes 58 and 60.

To effect the flushing function shaft 40 is 55 rocked by downward pressure on handle 44, thereby swinging finger 41 so that it passes into shallow notch 37, thus swinging arm 33 on its axis 34 and forcing float 35 downward into the water in the tank.

The inner end of arm 33 elevates block 31 so 60 that head 26 of stem 25 is lifted from aperture 24, thus permitting water under pressure within the chamber 15 to pass through aperture 24 and tube 21, thus permitting diaphragm 20 to flex upwardly under the influence of water flowing from supply pipes 14 and 13, through duct 17 beneath the diaphragm and then downwardly into the tubular member 18, from which the greater portion will flow through the elbow 57 into the tube 58.

As shaft 40 is rocked, arm 65 is swung upward, thereby elevating rod 64 and piston 61, so that port 62 is brought into registration with the ends of tubes 58 and 60 connected to cylinder 59 and thus the water carried from the tube 18 by the

tube 58 will be delivered to the tube 60, which will direct it through the aperture 56 in the tube 50 whence it will flow through apertures 51 into the lower portion of tube 45.

Thus it may be seen that when the handle 44 is depressed, the water under full service pressure is ejected almost instantly from the outlet end of the tube 60 into the central tube 50, the immediacy of this action being the result of connecting the tube 60 directly to the source of water under full pressure. This arrangement also causes water to be delivered into the tube 50 at such velocity that it issues from the orifices 51 in the lower end of the tube 50 also at considerable velocity. The rib 46 imparts a spiral motion to the water thus delivered at considerable velocity within the lower end of the tube 45 and this whirling motion is augmented by the spiral deflector 52. This whirling motion of the water flowing through the discharge pipe 12 causes it to have such velocity that it develops a relatively high vacuum within the upper end of the tube 45; and since the upper end of the tube 45 communicates through the apertures 55 with the interior of the sleeve 49, the lower end of which opens directly into the tank 10, a syphonic action is started whereby water within the tank 10 is drawn upwards through the sleeve 49, thence through the apertures 55 and downwardly through the tube 45 to the discharge pipe 12. The whirling motion of the water flowing through the tube 45 and discharge pipe 12 is maintained by both the external ribs 47 and the internal ribs 46. In this manner the water is caused to flow from the tank 10 to the toilet fixture in a smooth silent flow which practically eliminates the gurgling and hissing noises which constitute one of the objectionable features of toilet flush tanks of more conventional design.

When the water level within the tank lowers to such a point as to permit float 35 to rest in normal position on the surface of the water and lower a short distance therewith, notch 37 will move downward so as to release finger 41 and under the influence of weight 43 shaft 40 will rock back to its normal position so that arm 65 and rod 64 will move piston 61 downward. This will disconnect the tube 60 from the tube 58 by moving the port 62 out of registry therewith and will bring the lower end of the inclined port 63 into registry with the end of the tube 58 so that thereafter water flowing through the tube 58 will pass directly into the tank 10, causing the tank to be refilled.

As the water rises within the tank, the float 35 will return to its normal position and arm 33, swinging on its pivot 34 will finally move block 31 and stem 25 downward until head 26 closes aperture 24 and subsequently the pressure of water bleeding unto chamber 15 through tubular rivet 27 will act on top of diaphragm 20 and force same downward to cut off further flow of water into tube 18.

Adjustable tube 54 on the lower end of tube 53 provides means for breaking the siphonic action at selected elevation in relation to the bottom of the tank.

The modified constructions illustrated in Figs. 5 and 6 are especially designed as replacements for flush tanks originally equipped with standard "Douglas" fittings including a tubular member 70 seated in the bottom of tank 10a and connected to the tube leading to the bowl or urinal, the upper end of which member is provided with a seat for conventional hollow rubber valve and

said member 70 also being provided with a lateral tubular extension 71 to which is secured the lower end of a conventional overflow pipe 72.

In accordance with my invention, a tube 13 leads from the tank supply pipe 14 to a valve housing 15 having an inlet port 16 normally closed by a float-controlled valve 17 and with a lower outlet port 18 and an upper outlet port 19. Valve 17 is reciprocally disposed within a horizontal cylinder 15a formed in the valve housing 15.

An arm 30 carrying a float 30a is pivoted at 31 to a bracket on the valve housing 15, with a pin 32 between the end of said arm and valve 17. A finger 33 projects upwardly from the end of arm 30 above pivot 31, said finger having a deep notch 33a and a shallow notch 33b for the reception of a finger 34 carried by a rock shaft 35 provided on its outer end with a handle 35a. The parts just described are practically the same in structure as the float arm 33, notches 36 and 37, rock shaft 40, finger 41, and handle 44 herein previously described.

Extending through the vertical portion of member 70, is a tube 86 having an outlet 86a communicating with the duct through extension 71. The upper end of tube 86 is connected to one end of a laterally arranged tubular goose-neck 87, the other end of which extends downward and rests on the bottom of the tank, thus providing a trap 87a.

Depending from the upper portion of goose-neck 87 and disposed axially in tube 86 is a tube 88 provided in its upper portion with an air inlet aperture 88a. Surrounding the lower portion of this tube 88 is a slightly larger tube 89 provided with an externally arranged spiral flange 89a which imparts whirling motion to the water as it leaves the tank through the tube 86.

Seated in the bottom of that portion of the goose-neck having the trap 87a, is the lower end of a vertical tube 90 which provides a support for a larger vertical tube 91, the lower end of the latter communicating with the opening into trap 87a. The outer face of the tube 91 carries a spirally disposed flange 91a.

Surrounding tube 91 and its spiral flange is a shell 92 open at its lower end and closed at the top by a plate 92a, from which both the tube 91 and the shell 92 depend. The tube 91 and the shell 92 are in communication with each other at their upper ends through apertures 91b in the tube 91.

A tube 92b rigid with and surrounding the upper portion of the tube 90, supports the plate 92a, and the lower portion of said tube 90 is provided with outlet apertures 90a below the lower end of the tube 92b and communicating with the lower end of the tube 91. Secured to plate 92a is a depending tube 93, the upper end of which communicates with the upper end of the shell 92 and on the lower end of which is screw seated a short tube 93a, thus providing an adjustable siphon breaker that is similar in both construction and functions to the previously described parts 53 and 54.

Leading from valve housing 15 just below outlet port 18, is a tube 94 which extends downward, thence into the lower end of shell 92, thence upwardly between said shell and tube 91, thence through one of the apertures 91b to enable the discharge end of said tube 94 to extend into the upper end of tube 90.

Surrounding overflow tube 12 is a larger tube 75 95 open at its lower end and closed at its upper

end by cap 95b. Tube 95 is provided on its inner face with a spiral flange 95c. Secured to the center of cap 95b, is the upper end of a small tube 95d open at both ends and which extends through tube 72 and terminates within the lateral extension 71 of the outlet tube 70 in the bottom of the tank 10a.

Formed in the lower portion of the wall of tube 95 is an air inlet aperture 95a which admits air to the space between tubes 72 and 95 and within said tube 72 to break siphonic conditions therein, when the water level in the tank passes below said inlet aperture.

When valve 71 is opened by actuation of handle 85a water will flow from pipe 73 through port 76 into the valve chamber, thence out through port 78, through tubes 94 and 90 into trap 87a, thus setting up a suction through the gooseneck 87, tube 86 and outlet from the tank.

As the water passes through tube 86, spiral flange 89a imparts whirling motion to the water so as to accelerate its flow and as a result, storage water from the tank will be quickly drawn upward between tube 91 and shell 92, thence downwardly between tubes 91 and 92b to and through the gooseneck 87, thus accomplishing the flushing function. At the same time some of the water from the tank will, by suction be drawn upward between tubes 72 and 95, thence downward through said tube 72 to unite with the water discharging through tube 86.

Before valve 71 closes a certain amount of water will pass through refill tube 96 to refill the bowl or urinal.

In some instances it may be found desirable to eliminate the gooseneck 87 and as illustrated in Fig. 6 to mount the lower end of tube 91 in the upper end of tube 70 and said tube 91 carrying the associated parts 89 and 89a, guide tube 88, tube 91, shell 92, tubes 93 and 93d, also water pressure supply pipe 94.

The function of this structure is the same as that of the corresponding structure illustrated in Fig. 5 and hereinafter described.

The use of a gooseneck enables tube 91 and parts associated therewith to be located at any convenient point on the bottom of the tank within a radius of approximately 270 degrees from the outlet fitting 70.

It will be understood that minor changes in the size, form and construction of the various parts of my improved flush tank may be made and substituted for those herein shown and described, without departing from the spirit of the invention, the scope of which is set forth in the appended claims.

I claim:

1. In a toilet tank flushing apparatus, the combination with a tank having a water pressure supply pipe and an outlet, of a float-actuated valve for controlling the flow of water from said valve into said tank, an upright tubular member within said tank with its lower end in communication with the outlet from the tank, spirally disposed ribs on the inner and outer faces of the wall of said tubular member, means for inducing siphonic action comprising a duct for conveying water from said valve to the interior of said tubular member, a shell associated with said tubular member, and means closing the upper ends of said shell and said tubular member, said shell and said tubular member being in communication with each other adjacent their upper ends, and said shell opening at its lower end to the interior of said tank and thereby being adapted to con-

duct water stored within said tank upwardly to the top of said tubular member.

2. In a flushing apparatus, the combination of a tank having a water pressure supply pipe and an outlet, an inlet valve associated with said supply pipe to control flow therefrom to said tank, a float within said tank and operably connected to said valve to open said valve when said float is lowered, siphon means comprising a siphon outlet tube communicating at its lower end with said tank's outlet and tubular siphon inlet means communicating at its upper end with the upper end of said siphon outlet tube and at its lower end with the lower portion of the interior of said tank, a duct leading from said valve into position to discharge water therefrom into said siphon outlet tube, means for submerging said float to lowered, valve-opening position and thereby establishing flow through said duct to said siphon outlet tube to induce discharge of water stored within said tank through said siphon means, and means operable subsequently to inducing said discharge of stored water for diverting water flowing through said duct from said siphon means and discharging it into said tank.

3. In a flushing apparatus, the combination of a tank having a water pressure supply pipe and an outlet, an inlet valve associated with said supply pipe to control flow therefrom to said tank, a float within said tank and operably connected to said valve to open said valve when said float is lowered, siphon means comprising a siphon outlet tube communicating at its lower end with said tank's outlet and tubular siphon inlet means communicating at its upper end with the upper end of said siphon outlet tube and at its lower end with the lower portion of the interior of said tank, a duct leading from said valve into position to discharge water therefrom into said siphon outlet tube, means for submerging said float to lowered, valve-opening position and thereby establishing flow through said duct to said siphon outlet tube to induce discharge of water stored within said tank through said siphon means, means for retaining said submerged float in said lowered position until no longer supported therein by water stored within said tank and for thereafter releasing said float to permit return of said float to valve-closing position as said tank is filled, and means operable subsequently to inducing said discharge of stored water for diverting water flowing through said duct from said siphon means and discharging it into said tank.

4. In flushing apparatus, the combination of a tank having a water pressure supply pipe and an outlet, an inlet valve associated with said supply pipe to control flow therefrom to said tank, a float within said tank and operably connected to said valve to open said valve when said float is lowered, an upstanding tubular member within said tank with its lower end in communication with said tank's outlet, a shell surrounding and spaced from said tubular member, means closing the upper end of said shell, the upper end of said tubular member being in communication with the upper end of said shell and said shell opening at its lower end to the interior of said tank and thereby being adapted to conduct water stored within said tank upwardly to the top of said tubular member, a duct leading from said valve in position to discharge water therefrom into said tubular member and thereby induce siphonic action to discharge water stored within said tank through said shell and said tubular member when said valve is opened, means for

submerging said float to lowered, valve-opening position, and means operable while said float is in said lowered position for diverting water flowing through said duct from said tubular member and into said tank.

5. In flushing apparatus, the combination of a tank having a water pressure supply pipe and an outlet, an inlet valve associated with said supply pipe to control flow therefrom to said tank, a float within said tank and operably connected to said valve to open said valve when said float is lowered, an upstanding tubular member within said tank with its lower end in communication with said tank's outlet, a shell surrounding and spaced from said tubular member, means closing the upper end of said shell, the upper end of said tubular member being in communication with the upper end of said shell and said shell opening at its lower end to the interior of said tank and thereby being adapted to conduct water stored within said tank upwardly to the top of said tubular member, spirally disposed ribs on the inner and outer faces of said tubular member, a duct leading from said valve in position to discharge water therefrom into said tubular member and thereby induce siphonic action to discharge water stored within said tank through said shell and said tubular member when said valve is opened, means for submerging said float to lowered, valve-opening position, and means operable while said float is in said lowered position for diverting water flowing through said duct from said tubular member and into said tank.

6. In flushing apparatus, the combination of a tank having a water pressure supply pipe and an outlet, an inlet valve associated with said supply pipe to control flow therefrom to said tank, a float within said tank, an arm operably connecting said float to said valve to open said valve when said float is lowered, siphon means comprising a siphon outlet tube communicating at its lower end with said tank's outlet and tubular siphon inlet means communicating at its upper end with the upper end of said siphon outlet tube and at its lower end with the lower portion of the interior of said tank, a duct leading from said valve into position to discharge water therefrom into said siphon outlet tube, a shaft mounted for rocking movement within said tank, means accessible outside said tank for rocking said shaft, a finger rigid with said shaft, said arm having notches therein of different radial distances from the axis of said shaft and adapted selectively to receive said finger, said finger being adapted to lower said float into submerged, valve-opening position when moved into that one of said notches at the lesser radial distance from the axis of said shaft and to be retained within that notch until the water level within said tank is lowered sufficiently for said float and arm to move downwards away from engagement with said finger, and means operable by gravity for removing said finger from registry with said one of said notches when released from said arm and into registry

with the other of said notches whereby said float and arm are adapted to move to their uppermost, valve-closing position as said tank is filled.

7. In flushing apparatus, the combination of 5 a tank having a water pressure supply pipe and an outlet, an inlet valve associated with said supply pipe to control flow therefrom to said tank, a float within said tank, an arm operably connecting said float to said valve to open said valve when said float is lowered, siphon means comprising a siphon outlet tube communicating at its lower end with said tank's outlet and tubular siphon inlet means communicating at its upper end with the upper end of said siphon outlet tube and at its lower end with the lower portion of the interior of said tank, a duct leading from said valve into position to discharge water therefrom into said siphon outlet tube, a shaft mounted for rocking movement within said tank, means accessible outside said tank for rocking said shaft, a finger rigid with said shaft, said arm having notches therein of different radial distances from the axis of said shaft and adapted selectively to receive said finger, said finger being adapted to lower said float into submerged, valve-opening position when moved into that one of said notches at the lesser radial distance from the axis of said shaft and to be retained within that notch until the water level within said tank is lowered sufficiently for said float and arm to move downwards away from engagement with said finger, and means operable by gravity for removing said finger from registry with said one of said notches when released from said arm and into registry
